WINDOW LOCK

Stanley A. Jacques, 7009 Kittyhawk Ave.,
Los Angeles, Calif.

Filed Oct. 17, 1958, Ser. No. 767,819

8 Claims. (Cl. 292—63)

This invention relates to a window lock which is particularly adapted for use on conventional double hung windows.

It is an object of my invention to provide a lock of the class described which can be used to lock both windows, regardless of whether they are in closed position or in partially open position. Another object is to provide a lock which permits either or both of the windows to be moved toward closed position without releasing the lock and which at all times prevents movement of the windows toward an opened position.

A further object of my invention is to provide a lock which becomes more tightly locked when an attempt is made to move the windows toward an open position.

It is another object of my invention to provide a window lock which cannot be opened from the outside by the insertion of an object or by sudden movement of the window and which is provided with positive means for preventing intentional or accidental unlocking.

It is among the further objects of my invention to provide a lock of the class described which may also be used for holding windows which tend to fall; which may be used to prevent windows from rattling; which will not mar or damage the windows or window frames and which is provided with means for simplifying its proper alignment and installation.

It is accordingly among the objects of my invention to provide a window lock having all of the benefits and advantages set forth above and which is simple to install and operate and which is simple and economical to manufacture.

My invention also comprises such other objects, advantages and capabilities as will later more fully appear and which are inherently possessed by my invention.

While I have shown in the accompanying drawings a preferred embodiment of my invention, it should be understood that the same is susceptible of modification and change without departing from the spirit of my invention.

Referring to the drawings,

Fig. 1 is a perspective view on a reduced scale of my window lock in use on a conventional pair of double hung windows;

Fig. 2 is a side elevational view of my window lock in use and in locked position, with the radial lines and arcs indicating the eccentricity of the flange;

Fig. 3 is a sectional view taken on line 3—3 of Fig. 2;

Fig. 4 is a side elevational view similar to Fig. 2, showing the increased wedging action when the windows are moved;

Fig. 5 is a top plan view taken on line 5—5 of Fig. 2;

Fig. 6 is a side elevational view of my window lock in unlocked position, with its locked position indicated in dotted lines;

Fig. 7 is a top plan view of the same taken on line 7—7 of Fig. 6.

A preferred embodiment of my window lock which has been selected to illustrate my invention is adapted

2

to be used on either side of a conventional pair of double hung windows 10 and 11. It comprises a substantially triangular base 12, which is adapted to be mounted on the horizontal upper edge of the innermost window 10.

5 A plurality of screws 13 or other suitable fastener members are used to secure the base 12 to the window 10.

Extending vertically upwardly from the base 12 are a pair of spaced parallel arms 14 and 15, between the upper ends of which extends a horizontally directed shaft 16.

10 A lock member 17 is rotatably mounted at one end thereof on the shaft 16. The lock member 17 includes a narrow body portion 18 which carries at its outer end a substantially wider flange 19. The contour of the flange 19 is arcuate and off center with respect to the shaft 16.

15 A coil spring 20 surrounds the shaft 16, with one end bearing against the arm 14 and the other end bearing against the body portion 18 of the lock member 17 and normally urging it against the other arm 15.

20 The upper end of the arm 15 is rounded, but is slightly relieved on the side thereof toward the window 11 to provide a right angular stop portion 21. A stud 22 projects outwardly from one side of the body portion 18 of lock member 17 and is directed toward the arm 15. 25 The stud 22 is so disposed that upon rotation of the lock member 17 with respect to the arm 15, the stud 22 will engage the stop portion 21.

25 When my lock is not in use, the lock member 17 is rotated away from the window 11 to the position shown in Fig. 6 of the drawings. The stud 22 bears against the unrelieved portion of the arm 15, as shown in Fig. 7 of the drawings, with the coil spring 20 being compressed and urging the end of the stud 22 against the side of the arm 15. Both windows 10 and 11 are free for movement.

30 When my lock is to be used, the lock member 17 is rotated toward the window 11 to bring the flange 19 into engagement with the sash of the window 11. Rotation of the lock member 17 is continued until the stud 22 moves past the stop portion 21 into the relieved portion of the arm 15. The coil spring 20 then urges the lock member 17 laterally to bring the side of the stud 22 into a position adjacent the stop portion 21. The parts are then in the position shown in Fig. 2 of the drawings.

35 The arcuate outer surface of the flange 19 is off center with regard to the shaft 16, the clockwise portion of the flange 19 as shown in the drawings being an increasingly greater distance from the shaft 16. The lock member 17 thus acts as a wedge between the window 11 and the shaft 16 to press the windows 10 and 11 outwardly against their frames. If an attempt is made to move either window 10 or 11 toward open position, the eccentricity or cam action of the lock member 17 forces the windows 10 and 11 farther apart, as shown in Fig. 4

40 of the drawings. This causes the window sashes to bear even more tightly against the window frames and the frictional engagement between them makes it impossible to move either or both of the windows 10 and 11. It will be noted that the lock member 17 is itself light and the locking action is achieved by the friction between the windows and their frames resulting from the wedging action of the lock member 17.

45 The stud 22 and stop portion 21 act to prevent any accidental unlocking of the window lock by a sudden opening movement of the windows which might cause the lock member 17 to flip around out of locked position. Such movement is prevented by the engagement between the stud 22 and stop portion 21, which can be overcome only by moving the lock member 17 laterally 50 against the pressure of the coil spring 20 to move the stud 22 around the stop portion 21 so that the lock member 17 is free to rotate away from locked position.

The stud 22 and stop portion 21 also prevent intentional unlocking of the window lock from the outside by insertion of an object to rotate the lock member 17 toward open position. Once again, such rotation is prevented unless the lock member 17 is moved laterally as well as rotated.

It should be noted that the outer surface of the flange 19 is smooth, so that it rolls on the sash of the window 11 and does not mar or scar it. One of the principal advantages of my window lock, in addition to its security, is the fact that either or both of the windows 10 and 11 can be moved to a partially open position and my lock will still function in the same manner as if both windows were closed. It will permit either or both of the windows to be moved toward closed position, since such movement will not increase the wedging action of the lock member 17. It will, however, prevent the movement of either of the windows toward a more open position. It is thus possible for the user to be provided with adequate ventilation and still have security.

My lock is simple to properly install and align, since the user need only move the lock member 17 toward the window 11 with the stud 22 engaging the stop portion 21 and the flange 19 engaging the window 11. This is the proper position for mounting the base 12. In order to prevent loose windows from rattling, the user need only engage my window lock and then move either window slightly toward open position to increase the wedging action and force the windows against the frames to prevent rattling. Windows which tend to fall are held in position, since their falling will result in tighter locking.

I claim:

1. A window lock for double hung windows comprising a base adapted to be mounted on the upper edge of one of said windows, a pair of spaced parallel arms extending vertically upwardly from said base, a shaft extending transversely between and journaled at its opposite ends on said arms, a lock member rotatably mounted at one end thereof on said shaft, said lock member being movable laterally on said shaft, the other end of said lock member having a substantially wide flange, the outer edge of said flange being eccentric with respect to said shaft, the upper end of one of said arms being relieved on the side thereof adjacent the other of said windows, the relieved portion of said arm forming at the upper end thereof a substantially right angular stop portion, a stud carried by said lock member and projecting outwardly from one side thereof, said stud being directed toward the arm having a relieved portion, a coil spring surrounding said shaft, one end of said coil spring bearing against one of said arms and the other end of said coil spring bearing against the portion of said lock member adjacent said shaft, said coil spring normally urging said lock member laterally on said shaft toward the arm having a relieved portion, said lock member being rotatable with respect to said shaft to move the flange thereof into wedging engagement between said shaft and the other of said windows, the stud on said lock member being urged by said coil spring into the relieved portion of said arm, so that upon reverse rotation of said lock member said stud engages said stop portion to automatically prevent the release of said wedging engagement, said lock member being manually movable laterally on said shaft in the opposite direction against the urging of said coil spring to move said stud around said stop portion to permit the rotation of said lock member out of wedging engagement with the other of said windows.

2. A window lock for double hung windows comprising a base adapted to be mounted on the upper edge of one of said windows, a pair of arms extending upwardly from said base, a shaft extending transversely between said arms, a lock member rotatably mounted at one end thereof on said shaft, said lock member being mov-

able laterally on said shaft, the other end of said lock member having a flange, the outer edge of said flange being eccentric with respect to said shaft, the upper end of one of said arms being relieved on the side thereof adjacent the other of said windows, the relieved portion of said arm forming at the upper end thereof a stop portion, a stud carried by said lock member and projecting outwardly toward the arm having a relieved portion, a coil spring surrounding said shaft, one end of said coil spring bearing against one of said arms and the other end of said coil spring bearing against the portion of said lock member adjacent said shaft, said coil spring normally urging said lock member laterally on said shaft toward the arm having a relieved portion, 15 said lock member being rotatable with respect to said shaft to move the flange thereof into wedging engagement between said shaft and the other of said windows, the stud on said lock member being urged by said coil spring into the relieved portion of said arm, so that upon 20 reverse rotation of said lock member said stud engages said stop portion to automatically prevent the release of said wedging engagement, said lock member being manually movable laterally on said shaft in the opposite direction against the urging of said coil spring to move 25 said stud around said stop portion to permit the rotation of said lock member out of wedging engagement with the other of said windows.

3. A window lock for double hung windows comprising a base adapted to be mounted on the upper edge of one of said windows, a pair of arms extending upwardly from said base, a shaft extending transversely between said arms, a lock member rotatably mounted at one end thereof on said shaft adjacent one of said arms, said lock member being movable laterally on said shaft 30 the other end of said lock member having a flange, the outer edge of said flange being eccentric with respect to said shaft, said lock member being rotatable with respect to said shaft to move the flange thereof into wedging engagement between said shaft and the other of said windows, stop means engageable between said lock member and the adjacent arm to prevent rotation of said lock member out of wedging engagement with said window, a coil spring surrounding said shaft, one end of said coil spring bearing against the other of said arms 35 and the other end of said coil spring bearing against the portion of said lock member adjacent said shaft, said coil spring urging said lock member laterally on said shaft toward the adjacent arm into a position whereby said lock member upon reverse rotation thereof engages 40 said stop means, said lock member being manually movable laterally on said shaft in the opposite direction against the urging of said coil spring to disengage said stop means to permit the rotation of said lock member out of wedging engagement with the other of said windows.

4. A window lock for double hung windows comprising a base adapted to be mounted on the upper edge of one of said windows, a lock member rotatably mounted at one end thereof with respect to said base, the other 45 end of said lock member having a flange, the outer edge of said flange being eccentric with respect to the axis of rotation of said lock member, said lock member being rotatable to move the flange thereof into wedging engagement between said base and the other of said windows, stop means engageable between said lock member and base to prevent the reverse rotation of said flange out of wedging engagement with said window, and a coil spring engaging said lock member, said coil spring upon the rotation of said flange into engagement with said 50 window automatically moving said lock member into a position for engaging said stop means, said lock member being manually movable against the urging of said coil spring to permit the rotation of said lock member out of wedging engagement with said window.

5. A window lock for double hung windows compris-

ing a base adapted to be mounted on the upper edge of one of said windows, a lock member rotatably mounted at one end thereof with respect to said base, the other end of said lock member having a flange, the outer edge of said flange being eccentric with respect to the axis of rotation of said lock member, said lock member being rotatable to move the flange thereof into wedging engagement between said base and the other of said windows, stop means engageable between said lock member and base to prevent the reverse rotation of said flange out of wedging engagement with said window, and a coil spring engaging said lock member, said coil spring upon the rotation of said flange into engagement with said window automatically moving said lock member into a position for engaging said stop means, said lock member being manually movable against the urging of said coil spring to permit the rotation of said lock member out of wedging engagement with said window.

6. A window lock for double hung windows comprising a base adapted to be mounted on the upper edge of one of said windows, a lock member rotatably mounted at one end thereof on a fixed axis with respect to said base, said lock member being movable laterally on said axis, said lock member being rotatable into wedging engagement between said base and the other of said windows, stop means engageable between said lock member and said base to prevent rotation of said lock member out of wedging engagement with said window, a coil spring engaging said lock member, said coil spring upon the movement of said lock member into wedging engagement with said window automatically moving said lock member laterally on said axis into a position whereby said lock member upon reverse rotation thereof engages said stop means, said lock member being manually movable laterally on said axis in the opposite direction against the urging of said coil spring to permit the rotation of said lock member out of wedging engagement with said window.

7. A window lock for double hung windows adapted to be mounted on the upper edge of one of said windows, a lock member mounted for rotation into wedging engagement with the other of said windows, stop means for preventing rotation of said lock member out of said wedging engagement, resilient means engaging said lock member, said resilient means upon the rotation of said lock member into wedging engagement with said window automatically moving said lock member into a position for engaging said stop means, said lock member being manually movable against the urging of said resilient means to permit the rotation of said lock member out of wedging engagement with said window.

8. A window lock for double hung windows adapted to be mounted on the upper edge of one of said windows, a lock member mounted for rotation into wedging engagement with the other of said windows, stop means for preventing rotation of said lock member out of said wedging engagement, and resilient means engaging said lock member, said resilient means upon the rotation of said lock member into wedging engagement with said window automatically moving said lock member into a position for engaging said stop means, said lock member being manually releasable from said stop means to permit the reverse rotation of said lock member out of wedging engagement with said window.
